GRADE CROSSING GATE

Samuel Miskelly, Downers Grove, Ill., assignor to
 Western Railroad Supply Company, Chicago,
 Ill., a corporation of Delaware

Application September 15, 1944, Serial No. 554,309

2 Claims. (Cl. 39—7)

1

The present invention relates to railroad grade crossing gates and more particularly to a new and novel grade crossing gate-actuating mechanism which is so constructed and arranged as to provide a more efficient performance with an economical construction.

Grade crossing gates at the intersections of railroads and highways must be absolutely reliable in their operation. Economy of construction at the expense of perfection in operation cannot be tolerated. The gate must give the warning signal when the train is passing and it must give the clear signal and move to the clear position when the train and the danger have passed. Because of the absolute necessity of these requisites of performance gate signal constructions in the past have been expensive in construction.

It is an object of the present invention to provide a new and improved grade crossing gate. It is another object of the invention to provide a new and improved grade crossing gate-actuating mechanism. It is a still further object of the invention to provide a new and improved actuating mechanism for grade crossing gates in which the driving motor reaches substantially its full speed of rotation before assuming the gate-moving load. A still further object of the invention is to provide a gate-actuating mechanism in which the driving motor is normally declutched from the gate and is clutched thereto only upon reaching substantially its full speed of rotation, brake means being provided to prevent excessive speed of gate movement in either the up or down direction of travel. A still further object of the invention is to provide a grade crossing gate which moves to the "warning" position under the influence of gravity and which is raised to the "clear" position by a driving motor which is normally declutched except upon reaching substantially its full speed of operation. Another object of the invention is to provide a grade crossing gate in which the driving motor drives the gate both up and down, is normally declutched, and is connected to the gate only upon reaching substantially its full speed of operation. These and other more specific objects will appear upon reading the following specification and claims and upon considering in connection therewith the attached drawings to which they relate.

Referring to the drawings in which preferred embodiments of the present invention are disclosed and in which the same reference characters refer to the same parts throughout:

2

Figure 1 is a front view looking toward the railroad track at a grade crossing gate construction in accordance with the present invention and with the gate arm positioned in the raised or "clear" position;

Figure 2 is a vertical section through the gate-actuating mechanism upon the line 2—2 of Figure 1;

Figure 3 is a vertical section upon the line 3—3 of Figure 2;

Figure 4 is a section upon the line 4—4 of Figure 2 and shows a contact-actuating cam;

Figure 5 is a front view of the slot mechanism; Figure 6 is a side view of the slot mechanism;

Figure 7 is an end view of the centrifugal brake looking in the direction of the arrows upon the line 7—7 in Figure 2;

Figure 8 is an electrical circuit diagram showing the electrical connections including the track circuit when the gate is to be driven upwardly only;

Figure 9 is a circuit diagram similar to Figure 8 but showing the connections when the gate arm is to be driven both upwardly and downwardly.

Referring now to Figure 1 in particular a complete crossing gate constructed in accordance with the present invention is illustrated. A mast 1 having a base 2 is securely fastened upon a concrete foundation. The mast supports and carries a stop sign of a common and well known type, indicated by the reference character 3, which carries the usual warning "Stop on red signal" which may be of any suitable material and which preferably is light-reflecting. A second sign, indicated by the reference character 6, carries an indication of the number of tracks guarded by the gate or gates, and in the present instance reads "2 Tracks." Cross arms 7 and 8 carry the usual wording "Railroad crossing" formed of letters which are also preferably light-reflecting. Flashing lights 9 are secured to the mast by suitable means 11 and preferably include hoods 12 and background discs 13.

The main housing of the gate-actuating mechanism is indicated at 14 and is secured to the mast about four feet above the ground by suitable securing means 16. Within housing 14 is positioned the actuating mechanism for the gate arm which will be hereinafter disclosed. As illustrated in Figure 1, however, it is seen that the gate arm 17 is pivotally carried upon a supporting shaft 18 which extends transversely thru the housing, one side of the gate arm being extended a short distance beyond the pivotal axis 55 comprising the shaft 18 and carrying an arm-

counter-balancing weight 19. With the gate in the vertical position the weight 19 is positioned substantially directly below the pivotal axis 18 of the gate arm while with the gate in horizontal position the counterweight moves to the dotted line position. Weight 19 is preferably adjustable toward and from the pivotal axis 18 to permit adjustment of its counterbalancing effect.

The housing 14 for the gate-actuating mechanism is provided with a removable cover 21 which may be pivoted outwardly and downwardly upon its supporting means 22 by the use of its handle 23 provided for that purpose. The movement of the cover 21 to its open position operates to expose the gate-actuating mechanism positioned within the housing which, when viewed from the front, appears as is illustrated in Figure 2.

The gate arm shaft 18 is rotatably mounted in bearings the housings of which are indicated at 26. To drive the gate there is provided a motor indicated generally by the reference character 31 which includes a shaft 32 which extends substantially parallel to the gate shaft 18 and which is connected thereto through suitable gearing means and a centrifugal clutch as will now be described.

Beginning with the gate-carrying shaft 18 a toothed sector 34 is fixedly connected thereto and meshes with a pinion 36 keyed to a shaft 37 which extends parallel to the gate-carrying shaft 18. At its opposite end a large gear 38 is carried fixedly upon the shaft 37 and meshes with a second pinion 39 upon a stub shaft 41 which also carries a second large gear 42. The latter gear in turn meshes with a third pinion 43 carried by a second stub shaft 44 to which is keyed a third large gear 46 which meshes with a small gear 47 carried by a final shaft 48 positioned in alignment with the motor shaft 32. The gear reduction is such that the shaft 48 rotates approximately 700 times for each rotation of the gate-carrying shaft 18.

Motor shaft 32 is connectible to gear-carrying shaft 48 by means of a centrifugal clutch indicated generally by the reference character 51 and which includes a suitable friction surface 52 carried by a plate 53 rotatable with the motor shaft 32. Pivoted centrifugally operable clutch fingers 54 which are carried by the plate 51 and which may be, if desired, spring urged to open position, function to draw a juxtapositioned clutch plate 56 upon the shaft 48 against friction disc 52. Actually the operation of the weighted centrifugal clutch fingers at the predetermined speed of motor operation may be merely to move the motor shaft 32 axially within its permitted range of end movement and to shift the friction disc 52 into holding contact with the clutch plate 56. The clutch 51 is characterized in that until the motor 31 has reached a predetermined speed of rotation, preferably approximately its full speed, the clutch will not close and the motor will not assume the driving load. This relationship permits the use of a relatively small driving motor instead of a larger more expensive motor having a higher torque at reduced speeds of operation.

To prevent excessive speed of rotation of shaft 48, and so excessive speed of travel of the gate arm 17 in either direction, a centrifugal brake is provided, the rotating parts of which are carried by the shaft 48. The brake, clearly illustrated in Figure 7, includes a cylindrical housing 61 fixedly mounted upon a bracket 62 in the casting 14. Within the housing 61 and fixedly keyed to the shaft 48 by means of a retaining screw 62 is a radially extending plate the outlines of which

are shown in dotted lines and which is indicated by the reference character 63. Plate 63 carries three pins, two outer pins 64 at substantially the same distance from the axis of rotation, and a third pin 66 at a lesser distance. Positioned adjacent the plate 63, and also within the brake housing 61, is a second plate 67 upon which are mounted brake shoes 68 upon pivot pins 69. Plate 67 is loosely mounted upon the carrying shaft 48 and is provided with an arcuate slot 71 of limited extent into which extends the axially-extending pin 66 on the plate 63. The travel of the pin 66 in the slot 71 fixes the relative movement permitted between the plates 63 and 67.

Between the outer movable end of each pivoted brake shoe 68 and the radially fixed pivot pin 69 of the other brake shoe there extends a coiled tension spring 72. Spring 72 is not connected directly to the outer end of a brake shoe 68 but instead connects to a bell crank lever 13 pivoted on the shoe and formed with an inner end 74 sloped as a cam and which abuts a shoe-carried pin 76 to limit its pivotal movement under the force of the spring.

The cam end 74 of each spring-attached lever 13 is positioned circumferentially adjacent a pin 64 on the plate 63 rigid with the shaft 48. With the shaft 48 rotating in one direction and with the pin 66 in one end of the slot 71, that illustrated in Figure 7, the pin 64 will be spaced from the cam surface 74 and the initial tension of the spring 72 opposing outward travel of the brake shoe 68 will be the normal tension of the spring. With the shaft 48 rotating in the opposite direction, however, and with the pin 66 moved to the opposite end of the slot 71 from that illustrated in Figure 7, a pin 64 will have moved into contact with the cam end 74 of each pivoted lever 13 resulting in the pivotal movement thereof and in the placing of an additional tension in the spring 72. A greater resistance to the outward radial travel under centrifugal force is thereby provided the brake shoe 68. In operation this means that with the shaft 48 rotating in one direction the spring 72 will exert a greater resistance than in the other direction, and accordingly in the first-mentioned direction of rotation a higher speed of rotation of the shaft will be permitted before the brake shoes 68 fly outwardly into contact with the brake housing 61 to provide a braking action. The arrangement is such that the levers 13 are cammed inwardly during the movement of the gate arm moving to the upper or "clear" position and accordingly the gates are permitted to move to the "clear" position faster than they are permitted to move downwardly to the "warning" position. In a preferred embodiment the time of upward travel is seven to eight seconds and the time of downward travel twelve to fourteen seconds.

It is desirable to provide means whereby the gate arm is held in its upper "clear" position when the protected track is clear and this is accomplished by providing what is known as a slot, as illustrated in Figures 6 and 7, which comprises a pair of electrical magnets 81 provided with movable armatures 82. A pivoted bell crank lever 83 is spring-pressed against the armature 82 at one end and at its opposite end carries a pivoted lever 84 which in turn carries a pawl 86 pivoted at 87 and normally drawn downwardly by a coil spring 88 against an abutment pin 89. Pawl 86 is adapted to engage a ratchet wheel 91 carried by the shaft 48, the ratchet teeth being so shaped that when engaged by the pawl the

shaft 48 is locked against rotation in a direction which would result in the lowering of the gate arm. The engagement of the pawl with the ratchet wheel takes place whenever the slot is energized and the bell crank lever 83 is pivoted to effect the lowering of the pawl-carrying lever 84. With the slot de-energized the bell crank lever 83 drops away from the solenoid, the lever 84 is pivoted upwardly, and the pawl 86 is moved out of contact with the ratchet wheel teeth whereupon the shaft 48 is free to rotate and the gate arm 17 moves to its horizontal "warning" position.

It is necessary to provide means whereby the driving motor is energized and de-energized in the performance of its arm-actuating function. In one preferred embodiment of the invention as illustrated in Figure 8 the motor is connected to drive the gate arms up only. In the second preferred embodiment illustrated in Figure 9 the motor drives the gate arms both up and down. With either circuit connection, however, it is necessary to provide means within the mechanism itself whereby the motor and the slot will be energized and de-energized upon the gate arm reaching certain angular positions. This is accomplished by providing a plurality of contact-actuating cams upon the rotatable gate shaft 18. One of these cams, which may be taken as illustrative, is clearly shown in Figure 4, being indicated by the reference character 96. A movable contact bearing the reference character 97 is urged against the cam by its own resilience and is adapted to cooperate with a stationary contact 98. In certain angular positions of the gate arm shaft 18 the rigidly connected cam 96 will hold the contacts 97 and 98 open while in other angular positions the cam 96 will be so positioned that contact 97 under its own resilience will close upon contact 98. While but a single contact-actuating cam and actuated contact is illustrated in Figure 4 it is to be understood that as many of these are provided as is necessary. The cams, it should be understood, are to be angularly spaced upon the shaft 18 to accomplish the actuation of the contacts in the desired angular positions of the gate arm.

Referring now to Figure 8, in particular, a circuit diagram is illustrated in which the driving motor, indicated by the reference character 31 is adapted to drive the gate arm upwardly only, the downward movement being accomplished by gravity. The signal is arranged to protect a pair of tracks, each comprising a pair of rails 101 divided into insulated sections by insulators 102. Across each insulated track section is a battery B and also a track relay 103, each relay being provided with a pair of movable contacts 106 and 107. Movable contacts 106 are connected in series by a lead 108. The movable contact 107 of one relay is connected through a connector 109 to one of the front contacts 111 of the other relay which cooperates with the remaining movable contact 107, thereby placing movable contacts 107 in series. The front contacts 112 and one of the relays 103 are connected to a source of positive current through leads 113. Each relay 103 is provided with a back contact 114 for the movable contacts 107, the back contact being through a common lead 116 to common. Movable contacts 106 are connected in series with the winding of a relay 119 by means of a connector 121 connected to a front contact 111 of relay 103. Relay 119 is connected to a

common ground through a conductor 122 and is provided with a pair of movable heavy duty contacts 123 which are directly connected to a current source and which make contact with front contacts 124 which are connected through a conductor 126 with the front contact 98a cooperating with a movable contact 97a which is cam-actuated as previously described.

The movable contacts 107 of the track relays 10 103 which are connected, as stated, in series are connected by a lead 127 directly to the winding of a delayed action relay 128 the opposite side of which is connected through lead 129 to ground. Relay 128 includes a movable contact 131 connected directly to a positive power source and which cooperates with a front contact 132 connected by means of a lead 133 to the high resistance winding 134 of the aforesaid slot 81. High resistance solenoid 134 is connected through a lead 136 to the low resistance solenoid winding 137, the connector 136 being connected through a lead 138 to a ground and also through a lead 139 to one side of the motor 31. The opposite side of the winding of solenoid 137 is connected through a lead 141 to a second cam-actuated contact 97 the front stationary contact 98 of which is connected through a lead 142 to the aforementioned movable contact 97a. The latter is directly connected by means of a lead 143 to the field of the motor 31.

The operation of the signal when connected in the circuit as illustrated in Figure 8 is as follows: Upon a train approaching the highway upon either of the two tracks, and upon entering a track section between the insulators 102, the battery B is shorted and the relay 103 de-energized whereupon it drops its movable contacts 106 and 107. Regardless of which relay 103 is de-energized the opening of contacts results in the de-energizing of quick acting relay 119 which promptly drops its movable contacts 123 thereby de-energizing the front contact 98a.

Relay 128 is also de-energized upon the dropping of movable contact 107 which, however, drops into contact with the back contact 114 thereby connecting the relay 128 to common. As the opposite side of the relay winding was originally so connected it thereupon becomes short-circuited and this increases the retardation to 45 three seconds or more in the release of the movable contact 131. An operating advantage accrues in that lights, bells, etc., which form no part of this invention have an opportunity to operate before the gate begins to lower. After the 50 passage of the delay period in the operation of relay 128 the movable contact 131 opens thereby de-energizing the holding coil 134 of the slot. As described the de-energization of the slot coil results in the upward movement of the slot lever 60 84 and the release of the ratchet wheel 91 by the slot-controlled pawl 86. Immediately the gate arm 17 begins its downward travel under the influence of gravity, the driving motor 31 remaining stationary and de-energized and disconnected 65 from shaft 48. The latter is rotated through the gear train previously described which connects it to the gate arm shaft 18.

Excessive downward speed of travel of the gate arm is prevented by the centrifugal brake 61 operating as described. The direction of movement of the shaft 48 with the gate moving downwardly is such that the pins 64 carried by the plate 63 are spaced from the cam end 74 of the levers 73. This means that the springs 72 are untensioned 70 and exert a minimum retaining force upon the

brake shoes 68 which are therefore permitted to fly outwardly at a lower speed of rotation to provide a relatively slow speed of downward travel of the gate arms thereby permitting traffic to clear.

The downward travel of the gate arms with the accompanying rotation of the shaft 48 has effected the rotation of the contact-actuating cams 96 of which there is one for each of the contacts 97 and 97a. The cooperating cam 96 is so positioned and contoured that movable contact 97 is normally closed with the gate arm between eighty-six degrees and ninety-three degrees, zero degrees being the horizontal position and ninety degrees being the vertical position. On the other hand the cooperating cam 96 for the contact 97a is so positioned and contoured that that contact is closed between eighty-three degrees and zero degrees. It is clear, therefore, that the downward movement of the gate arm resulted in the opening of contact 97 and the closing of contact 97a at eighty-six degrees and eighty-three degrees, respectively.

Upon the gate reaching its horizontal position the de-energized relay 103 remains de-energized so long as the train remains within the insulated section or sections and the parts remain as described, the slot and motor both being de-energized.

Upon the passing train clearing the insulated section, however, the short upon the battery B and the relays 103 is removed and the movable contacts 106 and 107 are picked up. Immediately relay 119 is energized and the movable contacts 123 thereof are picked up and current flows through the connector 126 to the front contact 98a, the contact 97a of which is closed thereon, and to the motor through the connecting lead 143. The opposite side of the motor being connected through the leads 139, 138 to ground the motor is instantly energized and the armature thereof begins to rotate. The motor does not pick up the load comprising the gate arm until it has reached substantially its full operating speed at which time the centrifugal force acting upon the pivoted clutch fingers 54 throws them radially outward with sufficient force to clamp the disc 56 to the driving plate 53 and compress the friction surface 52 therebetween. Thereupon the shaft 48 begins to rotate, the driving motor assumes its load, and the gate arm moves upwardly, the movement of the shaft 48 being transmitted to the gate arm 18 through described gear train.

In this direction of movement of the shaft 48 the pin 66 is at the opposite end of the slot 71 from that illustrated in Figure 7 and the pins 64 are in contact with the cam ends 74 of the pivoted levers 73. This results in the tensioning of the springs 72 which thereupon exert a greater restricting force upon the brake shoes 68. In terms of operating characteristics, this means that the shaft 48 can rotate at a higher speed without the brake shoes 68 being moved outwardly under centrifugal force into contact with the brake drum 61 and so an increased speed of upward movement of the gate arm is permitted. The upward movement of the gate arm requires substantially seven to eight seconds as compared to twelve to fourteen seconds for the downward travel.

The motor being in operation the gate arm continues its upward travel and at approximately eighty-three degrees the cam 96 acting upon the movable contact 97a effects the opening of that

contact with respect to its stationary contact 98a. While this contact was closed, however, current had been able to flow through the lead 142 to the front contact 98, through movable contact 97 to lead 141 and thence to the low resistance solenoid 137 of the slot 81 which resulted in the picking up of the movable armature 82, the opposite side thereof being connected through the lead 138 to ground. The picking up of the slot armature with the accompanying movement of the pawl 86 into contact with the rotating ratchet wheel 91 did not effect the locking or prevention of movement thereof due to the shape of the ratchet teeth. As illustrated in Figure 6, the shaft 48 can rotate in a counterclockwise direction due to the shape of the teeth of the ratchet wheel 91. Upon the opening of the contacts 97a, 98a, however, solenoid winding 137 is de-energized. Current continues to flow through the high resistance holding solenoid coil 134, the latter being connected directly to ground through the leads 136, 138 while its opposite side is connected to a positive current source through the lead 133 to the front contact 132 of the relay 128 the movable contact 131 of which is connected to positive current. The slot, therefore, does not open and the pawl 86 remains in position to prevent reverse movement of the ratchet wheel 91 corresponding to the downward travel of the gate arm. Upon the gate arm reaching substantially eighty-nine degrees from the vertical the movable contact 97 is moved to open position by its actuating cam 96. From approximately eighty-three degrees to its vertical rest position at substantially ninety degrees the gate arm travels through under its own momentum. Upon reaching the end of its travel further movement of the arm is prevented by the abutment of the toothed sector 34 rotatable with the gate arm shaft 18 against the resilient contact abutment 141, which may be of any well known design, for example, as shown more fully in applicant's co-pending application Serial No. 389,541 (Patent 2,362,710). If desired a similar resilient abutment 141 may be provided to contact the sector 34 at the opposite end of its travel when the gate arm moves into the horizontal position, abutments positioned to accomplish both functions being illustrated in Figure 3.

Referring now to Figure 9 a second circuit diagram illustrates the manner in which the gate-arm-actuating mechanism may be electrically connected in order that the driving motor will rotate in opposite directions and drive the gate arm both upwardly and downwardly. In this type of operation, as in that previously described, the centrifugal clutch 54 operates to connect the driving motor to its load only when the driving motor has reached substantially its full speed, and similarly the centrifugal brake 61 operates to prevent excessive speed of arm travel in both directions, the characteristic being as before that the upward speed of movement is greater than the downward speed.

In Figure 9 the parts which are identical to those illustrated in Figure 8 bear the same reference characters and only those parts which have been substituted or have been added are additionally identified. Each insulated track section 70 is again provided with a battery B and a relay 103 connected between its track rails 101. Movable contacts 106 and 107 of each relay 103 operate effectively as in the first-described embodiment. A quick acting relay 119 is again connected in series with the movable contact 106

by a lead 121 and has its opposite side connected by lead 122 to ground. Relay 119 again includes movable contacts 123, with front contacts 124 connected in the manner of the first embodiment, and also with back contacts 151 which are connected through a lead 152 to a third and additional front contact 98b cooperating with a movable cam-actuated contact 97b, these contacts being closed between forty-five degrees and ninety-three degrees, approximately. The latter is directly connected by means of a lead 153 to a movable contact 154 which is actuated by the slot armature 82 and which cooperates with a stationary contact 156. The exact construction of movable contact 154 and its stationary contact 156 is not important and may be of the type illustrated in applicant's co-pending application Serial No. 389,541 (Patent 2,362,710), it being only important that when the slot armature is picked up the contacts 154 and 156 are open and when the slot is de-energized, and the pawl 86 is in inoperative position, the contacts 154 and 156 are in contact. This contact is important for by carrying the drive down motor current over this contact it is insured that the motor cannot start pulling downwardly until after the hold-clear mechanism comprising the slot has been de-energized and released. The stationary contact 156 is directly connected by a lead 157 to the lead 143 between the field of the motor 31 and the movable cam-actuated contact 97a.

As in the first-described circuit the delayed action relay 128 is connected between the contacts 107 of the track relays and ground. As before a movable contact 131 of that relay connects to a positive source of current and its cooperating front contact is connected by a lead 133 with the high resistance winding 134 of the slot. In this form, however, relay 128 is provided with a second pair of contacts and for a purpose to be explained.

The cam-actuated relays 97, 98 and 97a, 98a are connected and operate as in the first embodiment.

In the present embodiment it is necessary that the motor reverse its direction of travel for the upward and downward movements of the gate arm and to effect this result it is necessary to provide a pole-changing relay indicated by the reference character 161. Relay 161 has its windings connected, by means of a lead 162, to an additional front contact 132 of the delayed action relay 128 which is also provided with an additional movable contact 131 connected to positive current. The opposite side of the winding of relay 161 is connected by a lead 163 to the lead 138 leading to the common ground. Relay 161 is provided with a pair of movable contacts 164 each of which is adapted to cooperate with front and back contacts 166 and 167, respectively. The front contacts 166 are connected to opposite sides of the armature of motor 31 as are the back contacts 167. As one movable contact 164 connects directly to the motor field through a lead 168 and as the other contact connects directly to the common ground lead 138 via a lead 169, it is clear that the direction of current travel through the motor armature is in reverse direction with the movable contacts 164 up and down. The relationship is such that with the relay 161 energized and the contacts 164 picked up the motor rotates in one direction while with the relay 161 de-energized and the contacts 164 dropped the motor rotates in the opposite direction.

The operation of the invention when connected for motor drive in both the upward and downward movements of the gate as illustrated in Figure 9 is as follows: A train entering an insulated track section between the insulators 102 effects the de-energization of the controlling relay 103 as described in the first embodiment. Immediately the movable contacts 106 and 107 drop downwardly effecting the de-energization of quick acting relay 119 and delayed action relay 128. The de-energization of relay 119 effects the dropping of contacts 123 against their back contacts 151 thereby effecting the passage of current to the front contact 98b through the movable contact 97b and lead 153 to the movable contact 154 which is slot-operated and held in the open position with respect to back contact 156 so long as the slot 81 remains picked up and in locking position.

After its period of delay relay 128 drops the movable contacts 131 to de-energize both the pole-changing relay 161, which is connected thereto through the lead 162, and also the holding coil 134 of the slot which is connected thereto through the lead 133. It is to be noted that the slot 81 is de-energized and so the ratchet wheel 91 released before the motor is energized. The slot being de-energized the movable contact 154 drops onto its back contact 156 and positive current is passed to one side of the motor field. Current flows therefrom through a lead 168 to a movable contact 164 of the solenoid 161 in the dropped position, the solenoid being de-energized, through the motor armature and to ground through a second movable contact 164, the lead 169 and through the lead 138 to common. The slot being released the gate arm is free to move downwardly. The motor 31 is energized and, upon reaching its full speed of operation, drives the gate downwardly as previously described. Upon reaching substantially a forty-five degree position contact 97b is moved by its cooperating cam to its open position thereby de-energizing the motor and the gate moves the remaining distance to its horizontal position under gravity and under the momentum required by the motor propulsion. In the downward movement of the gate movable contact 97a closes at eighty-three degrees but no current flows therethrough, connecting lead 126 being open-circuited at the de-energized relay 119.

After the train has passed through the insulated section the controlling relay 103 is again energized whereupon the relays 119 and 128 are immediately energized being connected to the movable contacts of relay 103 as described. Positive current now passes through the movable contacts 123 of relay 119 to the upper contacts 124 and through the lead 126 to the stationary contact 98a. Contact 97a being closed between zero degrees and eighty-three degrees current is passed directly through lead 143 to one side of the motor field and through lead 142 to the stationary contact 98.

The picking up of relay 128 effects the movement of the movable contacts 131 thereof into contact with the stationary front contacts 132. Immediately current flows through lead 162 to the pole-changing relay 161 which effects the movement of the movable contacts 164 upwardly from contact with the back contacts 167 into contact with the front contacts 166. Accordingly the direction of current flow through the motor armature is reversed. The motor is energized, one contact 164 being connected to ground and the

other to the motor field, as described, and begins to rotate assuming the load of moving the gate upon reaching substantially its full speed of rotation by virtue of the operation of the centrifugal clutch 51.

As the gate moves upwardly under the actuation of the motor at substantially the eighty-six degree position contact 97 closes upon contact 98 thereby energizing the pickup winding 137 of the slot 81 which moves the pawl 86 into locking position with regard to the ratchet wheel 91. The high resistance holding coil 134 had been previously energized by the pickup of movable contact 131 of relay 128 to which it is connected via lead 133 and front contact 132. Coil 134, however, does not exert sufficient force to actuate the slot armature 82 although capable of holding it in a set position. At substantially eight-nine degrees in the clearing movement movable contact 97a is cam-moved to its open position and current to both the motor, through the lead 143, and to the pickup coil 137, through the contacts 98, 97 and lead 141, is cut off. Current to the same side of the motor from the contact 97b had previously been cut off with the picking up of the slot armature and the opening of contacts 154, 156 connected between the leads 153 and 157. The slot remains picked up, however, as the holding coil remains energized. The motor is thus de-energized and the holding slot energized and again the arm movement is stopped by the contact of the sector 34 with the resilient abutment 141 and thereafter is retained in the clear position by the holding coil.

I claim:

1. In a railroad crossing signal, a gate arm pivoted upon an horizontal axis for travel between a vertical "clear" position and a horizontal "warning" position, counterbalancing means carried by said arm proportioned to allow said arm to lower by gravity to warning position, a driving motor having a shaft, a normally open centrifugal friction clutch including centrifugally actuated elements carried and actuated by said shaft, a second shaft, a complementary part of said centrifugal clutch carried by said second shaft, a centrifugal brake including a stationary part and centrifugally actuated elements mounted on said second shaft, speed-reducing gear means connecting said second shaft to said gate, said brake being normally inoperative to permit the gate arm to start lowering by gravity freely and being rendered operative by a predetermined speed of said second shaft to brake the lowering of said arm,

said brake being further actuated by the speed of the second shaft during raising of the gate arm for opposing the driving force of the motor exerted through said clutch, and slot means connected to said second shaft to hold said shaft against and to release said shaft for rotation independent of the rotation of said first shaft.

2. In a railroad crossing signal, a pivoted gate arm counterbalanced for self lowering by gravity, a driving motor, a centrifugal friction clutch normally open and having centrifugal elements and a driving plate actuated by the motor when the clutch is open for closing the clutch, a shaft and a driven plate carried thereby for said clutch normally free of said driving plate, speed reducing power-transmitting means connecting said driven clutch plate shaft with said arm, a normally free centrifugal brake connected to said driven clutch plate shaft and adapted to be driven by said power-transmitting means, said brake being centrifugally actuated to limit the speed of rotation of said arm in either direction, gravity releasable electrically energized means connected with said clutch plate shaft for holding the gate raised, the counterbalancing and the power-transmitting means and the normally open clutch cooperating in allowing the gate to lower by gravity when the motor is not energized and without causing rotation of the motor upon the release of said releasable means and thereby actuating said brake to control the rate of descent of said gate, said friction clutch permitting simultaneous different speeds of the driving and driven plates whereby overloading of the motor is rendered less likely and the speed limiting action of the brake may be effective even when said clutch is closed.

SAMUEL MISKELLY.
